DISPOSABLE EXHAUST FILTER

De Roy Simpson, 817 29th St., Oakland 8, Calif.

Filed Nov. 7, 1961, Ser. No. 150,757

2 Claims. (Cl. 55—446)

This invention relates to new and useful improvements in filters for use particularly but by no means necessarily, in restaurant, home and other forced air exhaust systems.

Substantially all filters presently in use in restaurant exhaust systems are of the washable type and of rather expensive construction. These filters, although heavy and difficult to handle, must be periodically removed, washed and replaced. Accordingly, it is the primary object of the present invention to provide an exhaust, etc., filter wherein disposal after a single installation or use is economically feasible.

Another highly important object of the invention is to provide a disposable filter of the aforementioned character which may be fabricated in a novel manner from a suitable material which is inherently absorbent, fire-resistant and readily available such as, for example, asbestos.

Still another important object of the present invention is to provide, in a manner as hereinafter set forth, a disposable, one-time use exhaust filter of the character described which may be of any suitable size or capacity and which, further, may be readily installed in single or multiple units as may be required.

Another object of the invention is to provide a disposable exhaust filter of the character set forth which is adapted to be expeditiously installed in any suitable frame or holder.

Other objects of the invention are to provide a disposable filter which will be comparatively simple in construction, strong, durable and of rigid construction, compact, of light weight and which may be marketed at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

FIGURE 1 is a view in front elevation of a disposable exhaust filter constructed in accordance with the present invention;

FIGURE 2 is a fragmentary view in transverse section on an enlarged scale, taken substantially on the line 2—2 of FIGURE 1;

FIGURE 3 is a fragmentary view in horizontal section on an enlarged scale, taken substantially on the line 3—3 of FIGURE 1; and

FIGURE 4 is a diagrammatic view in transverse section through the device, showing the flow of air therethrough.

Referring now to the drawing in detail, it will be seen that the embodiment of the present invention which has been illustrated comprises a generally rectangular frame 5 of suitable dimensions. Mounted vertically in the frame 5 are series of spaced, opposed baffles 6. It will be noted that the front baffles 6 are spaced inwardly from the front of the frame 5 and that the rear baffles 6 are flush with the rear of said frame.

The baffles 6 include right angularly bent upper flaps or flanges 7 the uppermost of which are adhered to the top 8 of the frame 5 and end flanges 9 which are adhered to the end members 10 of said frame. The baffles 6 further comprise lower flanges 11 which are folded on themselves to interlock with the flanges 7 of the subjacent baffles to which they are adhered. As shown to advantage in FIGURE 2 of the drawing, the right portions of the U-shaped flanges 11 abut and are adhered to the

2

opposed lower portions of the adjacent baffles as at 12 in a manner to provide a rigid unitary structure.

The baffles 6 comprising the flanges 7, 9 and 11 define plenums 13 in the frame 5. Vertically staggered longitudinally elongated openings or slots 14 in the baffles 6 communicate the plenums 13 for the zigzag or tortuous flow of streams of air to be decontaminated through the device.

It is thought that the use of the invention will be readily apparent from a consideration of the foregoing. The complete device including the frame 5 is made of a suitable absorbent, fireproof or fire-resistant material which does not deteriorate when saturated with grease, cooking oils, etc. The device is installed in the intake end portion 10 of an exhaust duct to cleanse the air before it passes therethrough. As indicated by the arrows in FIGURE 4 of the drawing, the air flows through the unit in a multiplicity of zigzag or tortuous paths. Thus, the air is caused to impinge or wipe against the multiple surfaces of the baffles 6 which extract and absorb the grease, food particles and other foreign matter therefrom in an obvious manner. The construction and arrangement of the device is such that air passing therethrough undergoes several changes in velocity as well as in direction thereby creating turbulence in the filter for causing the air to contact the absorbent surfaces repeatedly. While the openings or slots 14 are small enough to cause decreases in the velocity of the air as it enters the successive plenums, said slots are also sufficiently large to avoid clogging by lint 20 and other material usually found in the air. The interlocking flanges 11 of the lowermost baffles 6 are adhered to the bottom member 15 of the frame 5. When the device becomes saturated or substantially so it is simply removed and discarded and a new or fresh unit is installed.

It is believed that the many advantages of a disposable filter constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed. For example, the material may be of a waffle design for increased efficiency. Also, in lieu of an inherently absorbent material such as asbestos, the unit may be made of an even less expensive material having on the surfaces thereof a viscous or sticky coating.

What is claimed as new is as follows:

1. A panel-like air filter adapted to be disposed in an airstream with the medial plane of the filter extending transversely of said air stream, said filter comprising a plurality of horizontally spaced and vertically extending reaches of vertically stacked and horizontally elongated upright baffles, corresponding baffles of adjacent reaches being generally horizontally aligned, each of said baffles having a plurality of horizontally elongated openings formed therein at points spaced longitudinally therewith, the openings in each reach of baffles being disposed adjacent one of the upper and lower edge portions thereof and the openings in adjacent reaches of baffles being inversely positioned relative to the corresponding ones of said upper and lower edge portions, corresponding openings in each reach of baffles being in substantial vertical alignment and corresponding ones of the openings in corresponding baffles being disposed in the same vertical plane extending transversely through said filter, the upper edges of the lower set of openings in corresponding ones of said baffles being spaced below the lower edges of the upper set of openings and the corresponding baffles of the adjacent reaches of baffles, and the vertical extent 55 of said openings being less than the spacing between adjacent ones of said reaches.

2. The combination of claim 1 wherein said baffles terminate at their lower ends in right angulated lower flanges extending longitudinally thereof, projecting outwardly therefrom a distance equal to the spacing between said reaches, and terminating in reversely bent portions at their free ends slightly vertically spaced from the corresponding right angulated flanges and defining therebetween horizontally disposed channels opening rearwardly in the direction in which the right angulated flanges extend outwardly from said baffles, said baffles terminating at their upper ends in right angulated upper flanges extending longitudinally thereof and projecting outwardly therefrom a distance equal to the space between said reaches, the free ends of said upper flanges being seated and secured in the corresponding channels, the bent portions connecting said right angulated and reversely bent

flanges having their outer surfaces abutted against and secured to the upper edge portions of the corresponding baffles.
